COMBINED GREETING CARD AND CARD HOLDER

John L. Krause, 3310 Thornberry Road, Glenview, Ill.

Filed Jan. 6, 1965, Ser. No. 83,286

Term of patent 14 years

(Cl. D59—2)

FIG. 1 is a perspective view of a combined greeting card and card holder showing my new design;

FIG. 2 is a side elevational view, the side opposite being a mirror image thereof;

FIG. 3 is a top plan view;

FIG. 4 is a bottom plan view;

FIG. 5 is an end elevational view, as seen from the left of FIG. 2;

FIG. 6 is an end elevational view as seen from the right of FIG. 2, and

FIG. 7 is a top plan view of the design shown in FIG. 1, as it appears in blank form.

I claim:

The ornamental design for a combined greeting card and card holder, as shown.
